SHOE SOLE

George H. Bingham, Jr., Westminster, and Otto Olson,
Taneytown, Md., assignors to Cambridge Rubber Com-
pany, Cambridge, Mass., a corporation of Maryland

Filed Dec. 14, 1962, Ser. No. 72,860

Term of patent 14 years

(Cl. D7—5)

FIGURE 1 is a side elevational view of a shoe sole embodying our new design, the broken line showing of the shoe upper being for purposes of illustration only;

FIGURE 2 is a bottom plan view of the shoe sole;

FIGURE 3 is a transverse sectional view, as seen on the line 3—3 of FIGURE 2;

FIGURE 4 is a vertical longitudinal sectional view in fragment, as seen on the line 4—4 of FIGURE 2;

FIGURE 5 is a bottom plan view of a shoe sole showing another embodiment of our new design;

FIGURE 6 is an enlarged fragmentary perspective view of a portion of the shoe sole shown in FIGURE 5 showing one of the supporting elements;

FIGURE 7 is a vertical transverse sectional view, as seen on the line 7—7 of FIGURE 5; and

FIGURE 8 is a vertical longitudinal sectional view, as seen on the line 8—8 of FIGURE 5.

We claim:

The ornamental design for a shoe sole, as shown and described.
